INSULATED ORNAMENTAL SIDING MATERIAL

Stanley S. Phillips, Norwood, Mass., assignor to
Bird & Son, Inc., East Walpole, Mass., a corporation of Massachusetts

Application April 8, 1939, Serial No. 266,796

5 Claims. (Cl. 20—5)

This invention relates to insulated ornamental siding material adapted for use as an outside weather-proof siding for building structures, and has particularly to do with such material having an ornamental brick simulating appearance, for example, of the general type disclosed in the U. S. patent to Odell, No. 2,021,577 of November 19, 1935. The present invention, however, represents a substantial improvement over the material of said patent as will hereinafter appear, particularly in appearance, although also with respect to the bond or union of the insulating board to the asphalt-saturated granular surface layer of felt material.

In accordance with the present invention, a sheet of felt is saturated with asphalt and then one side thereof is covered throughout by the addition of granular colored mineral material, the color of which conforms to the color of the mortar it is desired to simulate. To such granular surfaced layer there are then applied spaced areas of liquid asphalt arranged to simulate the courses of brick, following which, brick-colored granular particles are deposited thereon and adhered to said areas and only said areas so as to give additional weather protection and simulate bricks laid in a differently colored mortar, by virtue of the exposure of the background or mortar-colored particles in the form of narrow strips representing mortar joints between bricks. Following the preliminary manufacture of the outside exposed portion of felt with the granular material thereon, it is then attached to a relatively thick, stiff, though soft, fibrous base material by means of a layer of asphalt cement therebetween. Thereafter, and preferably promptly thereafter and before the liquid asphalt cementing medium has had an opportunity fully to stiffen and set up, the assembled insulated siding material is pressed by means of a die provided with flat surfaces adapted to bear against the brick-colored granular areas of the felt sheet and with narrow double-ribbed downward projections adapted to fit between said brick-colored areas, to bear against the intervening mortar-colored areas of the granular surface, the ribs of each pair presenting substantially vertical exterior sides terminating in lower blunt edge surfaces, and with inner converging side surfaces forming a connecting surface therebetween of concave contour. In this way, when the die is forced downwardly on to the siding, the ribs trim and even off the defining edges of the brick-colored areas forming indentations or grooves along the edges of the mortar line areas which impart to the intervening mortar line portions a convex formation similar to that of "bull-pointed" masonry. This convex forming of the mortar line portions is permitted partially because of the relatively soft underlying insulating board which

is compressed sufficiently under the pressure of the double-ribbed die portion so as to assist in temporarily forming said lines to provide a convex formation. Each rib exerts a relatively high localized pressure along and adjacent each brick-appearing portion so that the granules under each rib are pressed more heavily but without, however, forcing the granules of the indented lines so deeply that they are obscured by the underlying asphalt.

As a practical matter, in the manufacture of the product of this invention, the asphalt in the lines of the indentations is laterally displaced somewhat towards the center or raised portion of the mortar line as permitted by the space between the double-ribbed die members. Because of the soft character of the insulating base, the double-ribbed die members are able temporarily at least to press the saturated felt of the mortar line areas—or rather the edges thereof—down into the relatively soft fibrous base material. Even though the fibrous material along these lines may become somewhat "broken-down" no harm is done for usually the fibrous base material, because of its resiliency, tends to assume its original form, but the formation of the convex mortar lines is assisted by the soft fibrous character as just referred to.

The effect of the sloping siding indentations is to change the reflected light coming to the eye from the oblique surfaces thereof, as compared with the light coming from the substantially vertical surfaces normal to the plane of the siding, which define the bricks, with the result that this difference provides a striking likeness to "bull-pointed" brick masonry and with an appreciable desirable shadow effect not present in products heretofore made.

The simultaneous application of pressure to the brick-colored areas and to the intervening mortar-colored areas is also an advantage in that it tends to prevent undesirable flowing or displacement of the asphalt layer by which the granular surface strip is united to the fibrous base though, perhaps, thinning such layer immediately under the double-ribbed die portions. By applying pressure both to the mortar line areas and to the brick appearing areas there is no injurious tendency of the asphalt to be unduly squeezed or bulged so as to impair the surface appearances of the product.

In the drawing, which illustrates the preferred form of the invention—

Fig. 1 is a perspective view, partly in section, showing the exposed surface of the insulated ornamental siding made in accordance with this invention as applied to a building;

Fig. 2 is an enlarged cross-sectional view illustrating the indenting operation as hereinafter more fully described; and

Fig. 3 is an enlarged cross-sectional view of a modified construction in which the fibrous base material is made up of a number of laminated sheets.

Referring now to the drawing, the reference numeral 10 designates a section of brick-simulating siding made in accordance with the present invention, two such sections being shown in Fig. 1 applied to a building one above the other and joined together at their upper and lower edges respectively. Each section comprises a relatively thick fibrous base 11 and cemented to the upper surface of said base a layer 12 of asphalt-impregnated felt having on its upper surface a continuous coating 13 of granular covered asphalt, the granules of said coating being colored to simulate mortar, and in spaced areas on said coating 13, a second coating 14 of granular covered asphalt, the granule particles of this coating being brick-colored so that the upper surface of each section is provided with areas 15 simulating bricks surrounded by areas 16 simulating mortar. The fibrous base 11 may comprise a single relatively thick fibrous web, as in the instance illustrated in Figs. 1 and 2, or it may be composed of a plurality of laminated fibrous sheets 17, as in Fig. 3, said sheets being suitably secured together as by thin layers 18 of asphalt cement.

As shown in Figs. 1 and 2, the fibrous base 11 of each siding section 10 is provided along its upper edge with a recess 19 in its upper surface, and along its lower edge with a recess 20 in its under side, said recess 20 forming an extending tongue 21 corresponding in length and thickness to the recess 19 in the upper edge. As will be apparent, the tongue 21 of each section fits into the recess 19 of the next lower section in a vertical row to form a smooth lapped joint between the bases of said sections. Preferably, I also provide forlapping the asphalt-impregnated felt layers 12 of adjacent sections in a vertical row. To this end, I form the upper edge 22 of the layer 12 substantially flush with the lower edge of the recess 19, said edge 22 being preferably slightly above the upper edge of a laterally extending mortar-simulating strip 16, providing therebetween an area or strip 23. The coating 14 of asphalt covered with brick-colored granules which would normally be applied to the coating 13 in said area 23 is omitted and said area 23 is also depressed below the level of the areas 16, as may be done by cutting away slightly the upper surface of the fibrous base 11 below said area, or by pressing said area more deeply into the base, as indicated in Fig. 2, or both. The lower edge of the layer 12 of each section coincides with the lower edges of a row of brick-simulating areas 15 on said layer and extends beyond the lower edge of the tongue 21 in the fibrous base 11 a distance approximately equal to the width of the depressed area 23. Thus, when two siding sections are joined together in a vertical row, the lower edge of the layer 12 of the upper section overlies the upper edge 22 and depressed area 23 of the layer 12 of the lower section to form a substantially level joint which, since it coincides with an indented side edge of a mortar-simulating strip, is not apparent to the eye.

To form a weatherproof joint between the sides of adjacent siding sections in each horizontal row, the fibrous base 11 of each section extends beyond one side edge of the layer 12, as indicated at the right hand side of Fig. 1, while the layer 12 extends a corresponding distance beyond the opposite edge of the base 11 (not

shown in the drawing). Preferably, the joint coincides with the ends of certain brick-simulating areas on one of the joined sections, so that the junction line where adjacent said areas has a similar appearance to the indentations formed in the edges of the mortar-simulating areas, thus serving to disguise the junction.

In accordance with the present invention, the areas 16 simulating mortar are provided at their sides with indentations 24, each indentation having a substantially vertical outer side 25 (Fig. 3) corresponding with the edge of an adjacent brick-simulating area 15 and an inner side 26, preferably sloping inwardly as shown, these indentations serving to define the edges of the brick-simulating areas regularly and sharply from the mortar-simulating areas and to form the mortar-simulating areas between them into ridges with sloping sides. Preferably, as shown in Fig. 1, the indentations 24 are continuous around each brick-simulating area but are not extended across the juncture between vertical and horizontal mortar-simulating areas.

To form the indentations 24, I may press the siding between dies, preferably shortly after the impregnated felt layer 12 has been cemented to the fibrous base 11. In Fig. 2, there is illustrated a section of siding under pressure between dies suitable for the formation of these indentations. As there shown, the dies comprise a platen 27 having a recess 28 in one of its surfaces adapted to receive the fibrous base 11 of the siding and a second platen 29 having a generally smooth surface 30 provided at intervals, corresponding to the mortar-simulating areas 16 on the siding, with projecting indentation forming die members 31. These die members 31 may, as indicated in the drawing, be set in suitably formed recesses in the surface 30 of the platen 29, or said surface may be formed without recesses and said die members secured externally thereto.

Each die member 31 is, as shown, preferably adapted to form a pair of indentations 24 at opposite sides of a mortar-simulating area 16, and comprises a body portion 32 having smooth substantially vertical external sides 33 and provided in its lower surface with a longitudinal groove 34 having a substantially flat central portion and outwardly sloping sides 35 providing narrow substantially flat surfaces 36 between their lower edges and the lower edge of the adjacent external side 33. At points of juncture between die members 31, the ridges formed by the grooves in one of the die members are cut away so that the indentations will not be carried across either of the corresponding joining mortar-simulating areas 16 of the siding. The surface 30 of the platen 29 is also provided with a raised strip 37 along one edge adjacent one of the die members 31, said strip corresponding in location and size to the area 23 on the siding and acting to depress the asphalt-impregnated felt in said area below the surface of the areas 16 as previously described.

When the siding is compressed between the platens 27 and 29, the surface 30 of the platen 29 between the die members 31 contacts the surfaces of the brick-simulating areas 15 to impart the desired amount of pressure to these areas. If desired, said surface 30, between certain of the die members 31 may be provided with suitable ribs to form vertical corrugations in the corresponding areas 15, such as illustrated in Fig. 1. At the same time, the die members 31 are forced

down onto the mortar-simulating areas 16, the external sides 33 of the members passing downwardly past the corresponding edges of the areas 15 and acting to shear off any irregular extensions of said areas, and the lower surface of said members, due to their concave curvature, forming the areas 16 into side indented portions 24 and a convexly curved inner portion, as previously described.

In the drawing the upper surface of the fibrous base under the areas 16 is shown as partaking somewhat of the surface curvature produced in said areas by the die members 31, that is, the layer 12 where it underlies the ribs on the die members is pressed into the fibrous base, the base at such points being correspondingly compressed and "broken-down" to some extent by the high localized pressure exerted by the ribs. Such deformation of the fibrous base is, as previously stated, of material assistance to proper formation of the indentations and convexly curved mortar line portions between them. For this reason I employ as the base material, a fibrous material which, while sufficiently thick and stiff to form, with the capping layers, a suitably resistant insulating siding material, is yet sufficiently soft to be somewhat deformed by the pressure of the die members 31, in the manner indicated. As a preferred example of such fibrous base material, I give a fibrous water-laid insulating board, which may be a solid construction as shown in Figs. 1 and 2, or a laminated construction as shown in Fig. 3, weighing from 15 to 25 pounds per cubic foot, of the order of thickness of $\frac{3}{8}$ to $\frac{1}{2}$ inch and having an insulating constant of around .45.

While I have illustrated in the accompanying drawing preferred embodiments of the improved insulated ornamental siding of the present invention, and have described herein certain methods and materials as preferred for use in the formation of such siding, it will be understood that I do not intend thereby to limit the scope of the present invention thereto, and that changes may be made in said embodiments, methods, or materials without departing from the spirit and scope of the invention.

I claim:

1. An insulated ornamental siding material having, in combination, a relatively soft though stiff fibrous insulating base member, a waterproof sheet adhesively secured to said base member, brick-colored particles of granular material adhesively secured to said waterproof sheet and covering certain areas only of said sheet to represent a plurality of courses of spaced brick with narrow mortar-joint-simulating areas of contrasting color exposed therebetween, said mortar-joint-simulating areas presenting convex exposed surfaces with the edge portions thereof adjacent the brick-appearing areas deeply indented and with said waterproof sheet depressed into said base member.

2. An insulated ornamental siding material having, in combination, a relatively soft though stiff fibrous insulating base member, a waterproof sheet adhesively secured to said base member, brick-colored particles of granular material adhesively secured to said waterproof sheet and covering certain areas only of said sheet to rep-

resent a plurality of courses of spaced brick with narrow mortar-joint-simulating areas of contrasting color exposed therebetween, said mortar-joint-simulating areas presenting convex exposed surfaces with the edge portions thereof adjacent the brick-appearing areas deeply indented and with said waterproof sheet depressed into said base member, each said indented portion forming a substantially vertical side defining an edge of an adjacent brick-appearing area.

3. An insulated ornamental siding material having, in combination, a relatively soft though stiff fibrous insulating base member, a waterproof sheet adhesively secured to said base member, brick-colored particles of granular material adhesively secured to said waterproof sheet and covering certain areas only of said sheet to represent a plurality of courses of spaced brick with narrow mortar-joint-simulating areas of contrasting color exposed therebetween, said mortar-joint-simulating areas presenting convex exposed surfaces with the edge portions thereof adjacent the brick-appearing areas deeply indented and with said waterproof sheet depressed into said base member, each said indented portion forming a groove wider at the top than at the bottom and having a substantially vertical side at the outer edge of said mortar-appearing area.

4. An insulated ornamental siding material having, in combination, a relatively soft though stiff fibrous insulating base member weighing from 15 to 25 pounds per cubic foot, an asphalt-saturated felt sheet adhesively secured to said base member by a relatively thin layer of asphalt, a layer of mortar-colored granular particles adhesively secured to said sheet and completely covering the weather-exposed side of said sheet, brick-colored particles of granular material adhesively secured over said mortar colored layer and covering certain areas only of said layer to represent a plurality of courses of spaced brick with narrow mortar-joint-simulating areas of contrasting color exposed therebetween, said mortar-joint-simulating areas presenting convex exposed surfaces with the edges thereof adjacent the brick-appearing areas deeply indented and with said felt sheet depressed into said base member.

5. An insulated ornamental siding material having, in combination, a relatively soft though stiff fibrous insulating base member, an asphalt-saturated felt sheet adhesively secured to said base member by a relatively thin layer of asphalt, a layer of mortar-colored granular particles adhesively secured to said sheet and completely covering the weather-exposed side of said sheet, brick-colored particles of granular material adhesively secured over said mortar-colored layer and covering certain areas only of said layer to represent a plurality of courses of spaced brick with narrow mortar-joint-simulating areas of contrasting color exposed therebetween, said mortar-joint-simulating areas presenting convex exposed surfaces with the edges thereof adjacent the brick-appearing areas deeply indented, the asphalt-saturated felt sheet underlying said depressed portions being pressed into the fibrous base member.
